GRAIN DOOR

Michael J. Ford, Hartsdale, N.Y., assignor, by mesne assignments, of one-half to International Paper Company, New York, N.Y., a corporation of New York, and one-half to The Stanley Works, New Britain, Conn., a corporation of Connecticut

Filed July 29, 1959, Ser. No. 830,230
9 Claims. (Cl. 160—87)

This invention relates to a grain door or closure for freight vehicles.

An object of the invention is to provide a closure which may be readily installed by unskilled personnel in a minimum of time while at the same time providing an extremely sturdy door structure. A further object is to utilize a wrapper for the door panels as a means for completing the sealing of the door and the forming of a floor flap. A still further object is to provide a door in which the reinforcing metallic member is continuous so that the nails may be driven at any point along the side of the sections to the door frame. Other specific objects and advantages will appear as the specification proceeds.

The invention is shown, in an illustrative embodiment, by the accompanying drawing, in which—

FIGURE 1 is a perspective view showing a freight vehicle and a grain door embodying my invention applied thereto; FIG. 2, a vertical sectional view, on an enlarged scale; FIG. 3, a broken perspective view of door sections enclosed within a wrapper which is later employed to seal the door; and FIG. 4, an enlarged detail sectional view, the section being taken as indicated at line 4—4 of FIG. 1.

In the illustration given, A designates a railway boxcar provided with a door frame B, and C designates a closure for the door consisting mainly of the panels 10 and 11.

Any number of panels may be employed, but I prefer to use at least two panels in the manner illustrated in FIGS. 1 and 2. Each panel comprises a double core corrugated board. As shown best in FIG. 4, the corrugated core 12 is bonded to an outside paper liner 15, and the corrugated core 14 is bonded to an outer paper liner 13. Each of the cores 12 and 14 are bonded at their inner sides to a continuous metal sheet 16, which may be formed of aluminum, aluminum alloy, thin steel, tin, or other reinforcing metal, which provides a reinforcement for the corrugated board structure. Instead of the corrugated board, it will be understood that one may use fiberboard, the metal sheet 16 being embedded centrally within the fibers of the fiber board, the fibers being confined between liner sheets such as sheets 13 and 15, as illustrated in FIG. 4.

The sections 10 and 11 are preferably arranged for shipment one above the other, as illustrated in FIG. 3, and wrapped with a cover 17 formed of paper reinforced with sisal fibers, glass fibers, or the like, and the package may then be secured by straps 18, etc.

When the board is to be erected, I place the panels 10 and 11 in the position shown in FIG. 1 and secure them by nails 19 which must pass through the metal reinforcing sheet 16, since this is coextensive with the door panels. I next place the cover sheet 17 taken from the package shown in FIG. 3 and secure it over the panels 10 and 11 by the use of nails 20, a portion of the cover being extended over the door to form a flap 17a. A door or climb-rail 21 may then be secured in position and a pry-board 22 may be secured over the floor flap 17a.

The completed structure is effective in that the cover 17 extends over the line of separation between the panels 10 and 11 while also providing the sealing flap 17a over the vehicle floor.

The structure provided as described above may be

2

erected by unskilled persons because the nails passing through the border of each panel necessarily secure also the reinforcing metal sheet 16 while at the same time the line of separation between the panels is effectively covered by the outer sisal or fiber-reinforced wrapper. For shipment, the package is extremely compact and there is no waste because the wrapper itself is utilized in the final erection and sealing of the door. Further, the wrapper provides an additional seal about the side edges of the panels 10 and 11 after these have been secured in position.

While I have shown the door as a sectional door, with sections 10 and 11 combined, it will be understood that my new closure may be formed in a single panel with the central metal sheet continuous throughout.

While, in the foregoing specification, I have set forth a specific structure in considerable detail for the purpose of illustrating my invention, it will be understood that such details of structure may be varied widely by those skilled in the art without departing from the spirit of my invention.

I claim:

1. In combination with a freight vehicle having a doorway defined by spaced-apart, vertically-extending frame members, a plurality of identically dimensioned, flat-faced, rectangular panels, each of said panels having a longer edge disposed horizontally to position said panels across said doorway, each of said panels having shorter edges disposed vertically of said frame members, said panels being vertically superposed to form a temporary door for said doorway with said shorter edges being aligned to define the vertical sides of said door, each panel comprising external layers of fibrous material enclosing intermediate metal reinforcing means, nails extending through said layers and reinforcing means securing said panels to said frame members, and a flexible fibrous sheet overlapping said door at the vertical sides thereof, means securing said sheet in the overlapping portions thereof to said vehicle, said sheet having a dimension parallel to said vertical sides greater than said vertical sides to provide a floor flap portion, said nails securing said panels to said frame members independently of securing said sheet to said vehicle.

2. In combination with a freight vehicle having a doorway defined by a floor and spaced-apart vertical frame members, a plurality of identically dimensioned, flat-faced, rectangular closure panels each having a long dimension greater than the spacing between said frame members, said panels being positioned across said doorway interiorly of said vehicle in vertically superposed fashion with the long dimensions disposed horizontally and with the panels in overlapping relation with said frame members, each panel comprising external layers of corrugated material enclosing intermediate metal reinforcing means, said metal reinforcing means being coextensive with said panel layers so as to also overlap said frame members, nails extending through said layers and reinforcing means securing said panels to said frame members, and a paper sheet overlying said panels adjacent the faces thereof remote from said frame members, means securing said sheet to said vehicle, said sheet being generally rectangular and extending onto said floor, said sheet having a horizontal dimension greater than said panel long dimension, whereby said sheet extends horizontally beyond said panels, said nails securing said panels to said vehicle independently of securing said sheet to said vehicle.

3. In combination with a freight vehicle having a doorway defined by spaced-apart, vertically-extending frame members and a floor, a plurality of identically dimensioned, flat-faced, rectangular panels, each of said panels

comprising external layers of corrugated paperboard material and an intermediate metal sheet coextensive with said layers, said panels being arranged in vertical superposed fashion across said doorway and in overlapping relation with said frame members, and a paper sheet overlying said panels interiorly of said vehicle, said sheet extending horizontally beyond said panels to effect a side seal and extending onto said floor to provide a floor flap, nails securing said panels to said vehicle independently of securing said sheet to said vehicle or to said panels, and additional nails securing said sheet to said vehicle.

4. An article of manufacture adapted to provide a temporary closure for the doorway of a freight vehicle, comprising a plurality of identically dimensioned, flat faced, rectangular panels arranged in aligned relation to form a six-sided stack, each of said panels comprising external layers of fibrous material enclosing metal reinforcing means, a paper wrapper about said stack enclosing all of the sides thereof, said wrapper being dimensioned to overlap said panels when the same are arranged in coplanar abutting fashion to form a door closure, and strap means about said wrapper.

5. An article of manufacture adapted to provide a temporary closure for the doorway of a freight vehicle, comprising a plurality of flat faced, rectangular panels having substantially identical short and long dimensions, said panels being arranged in aligned relation to form a six-sided stack, each of said panels comprising external layers of corrugated paperboard material enclosing metal reinforcing means, a paper wrapper about said stack enclosing all of the sides thereof, said wrapper being generally rectangular and having one dimension greater than the long dimension of each of said panels and another dimension greater than the sum of the short dimensions of said panels, and strap means about said wrapper.

6. An article of manufacture adapted to provide a temporary closure for the doorway of a freight vehicle, comprising a plurality of flat faced, rectangular panels having substantially identical short and long dimensions, said panels being arranged in aligned relation to form a six-sided stack, each of said panels comprising external layers of corrugated paperboard enclosing metal reinforcing means, a paper wrapper about said stack enclosing all of the sides thereof, said wrapper being folded on two of said stack sides and having a dimension parallel to said sides greater than the sum of the panel dimensions parallel to said sides, whereby said sheet is adapted to overlap said panels when the same are arranged in coplanar, abutting fashion to form a door closure, and strap means about said wrapper securing said panels in aligned relation.

7. In a method of closing a vehicle doorway opening defined by vertically-extending frame members, the steps of providing at least a pair of flat door sections wrapped

with a fibrous wrapper, each section comprising fibrous layers with metal reinforcing means therebetween, said wrapper having an area when arranged in planar fashion greater than the composite area of said sections, unwrapping said sections and securing them in vertical superposed relation on said frame members to define a closure having upper and lower horizontal sides and a pair of vertical sides, and securing said wrapper to said vehicle in overlapping relation with the said closure lower horizontal and vertical sides.

8. In a method for closing a vehicle door opening defined by a floor and a door frame, the steps of providing a plurality of metal reinforced corrugated paper door sections wrapped in a paper cover, unwrapping said sections at a site of installation and securing them in superposed relation across the door opening, applying said cover to said sections while leaving a lower portion of the cover projecting interiorly of the vehicle to form a floor flap, and sealing said cover about the vertical edges of said superposed sections.

9. In a method of closing a vehicle doorway opening defined by a floor and spaced-apart vertical frame members, the steps of providing a plurality of identically dimensioned, flat faced, rectangular panels wrapped in a paper wrapper, said panels being arranged in aligned relation to form a stack, unwrapping said panels adjacent the door opening to be closed, securing said panels to said door frame members in overlapping relation therewith and with said panels in vertical superposed relation, each of said panels comprising outer corrugated paperboard layers enclosing metal reinforcing means, all of said layers and reinforcing means overlapping said frame members, and securing said wrapper over said panels and interiorly of said vehicle with said wrapper overlapping the superimposed panels along the lower horizontal side and vertical sides thereof to provide seals therealong.
